UNITED STATES PATENT OFFICE.

ERNEST H. COOPER AND STANLEY B. EARLE, OF LONDON, ENGLAND.

SAFETY-RAZOR.

1,140,664.

Specification of Letters Patent. Patented May 25, 1915.

Application filed October 6, 1913. Serial No. 793,687.

To all whom it may concern:

Be it known that we, ERNEST HERBERT COOPER and STANLEY BEAUMONT EARLE, subjects of His Majesty the King of England, 5 residing at London, England, have invented certain new and useful Improvements in Safety-Razors, of which the following is a specification.

This invention is for improvements in 10 safety razors of the type in which the blade is movable to lie and adapted to be held in alinement or substantial alinement with the handle for the purpose of stropping and cleaning the same, and being particularly 15 applicable to safety razors of this type in which in addition to the blade being movable as aforesaid the guard is movable to fold down toward or against the handle to admit of said stropping and cleaning, the improvements 20 will be hereinafter described in such application.

By the present invention considering a preferred embodiment of safety razor thereunder, a safety razor of the kind referred 25 to is obtainable in which means combined with the blade for holding the same from movement in either direction when in the "shaving" or "stropping" or "cleaning" position are effective also for varying the 30 amount of projection of the guard beyond the edge of the blade; provision being made for admitting and securing the requisite movement of the guard toward and away from the handle in accordance and preferably automatically with the said adjustment 35 of the blade and guard, and such automatic movement of the guard away from as well as toward the handle being advantageously obtained by a spring control combined there- 40 with; the present improvements comprehending a spring control so formed and arranged that the further advantage is afforded of preventing vibratory movement of the blade and/or guard.

45 In a less complete aspect of the present invention the provision for varying the amount of projection of the guard beyond the blade edge may be dispensed with if a cheaper article be desired, in which case by 50 suitably determining the fixed shaving position of the blade the said spring control combined with the guard is rendered effective for insuring precision of adjustment and for preventing vibratory movement of

the blade and the guard in the shaving position. 55

In order that the invention may be clearly understood and readily carried into effect reference may be had to the accompanying drawings, on which:— 60

Figure 1 is a side elevation of a razor constructed according to this invention. Fig. 2 is a sectional view thereof, the section being on line $x-x$ of Fig. 3. Fig. 3 is a rear view, and Fig. 4 is a front view. Fig. 65 5 is a sectional view of a razor with the blade and guard in the "stropping" position. Fig. 6 is a side elevation of a modified construction of a razor constructed according to this invention. Fig. 7 a sectional 70 view thereof. Fig. 8 a rear view, and Fig. 9 a front view thereof. Fig. 10 is a sectional view of another modified construction of a razor with the blade and guard in the "stropping" position. Fig. 11 is an enlarged sectional view of a detail of the razor 75 according to Figs. 6 to 10.

We will describe a construction of safety razor which embodies the present improvements. A blade holder 1, in which a blade 80 2 may be detachably secured in any desired manner, is pivotally mounted in a U-shaped frame 3 secured at the top of a tubular handle 4 the holder being capable of movement about the pivotal axis. Pivotally secured to a tail piece 5 of the said blade holder 1 is a link 6 which is pivoted at its other end to the upper end of a rod 7 which passes through the tubular handle 4 so as to be capable of reciprocatory movement there- 85 in, means being combined with the rod for finely adjusting this in the "shaving" position of the blade and the guard. Thus the handle is provided according to the example selected with a groove 8 furnished with or 90 without notches or the like and inclined at a small angle to a plane at right angles to the rod 7, with which groove engages a pin projecting from the interior of a cap or thimble piece 14 to which the reciprocatory 100 rod is secured to move therewith. By slightly turning the cap or its equivalent on the lower end of the handle the cutting edge of the blade when this is positioned in shaving relationship with the guard may be 105 moved nearer to or farther away from the forward end of the guard. Provision may be made as by means of the groove 8^a form-

ing a continuation of the groove 8 and being substantially parallel to the axis of the rod, for giving a fast movement to the reciprocatory rod in order to facilitate the changing 5 of the blade from the "shaving" into the "out of shaving" position or vice versa which is accomplished by moving the rod upwardly or downwardly respectively, the groove 8 serving to lock the blade in the 10 "shaving" position while the groove 8^b forming a continuation of the part of the groove 8^a and having a corresponding inclination to that of the groove 8 serves to lock the blade in the stropping or cleaning 15 position.

Preferably the guard 9 is pivotally arranged so that it may be folded down toward or against the handle 7, and a spring control is combined therewith to hold the 20 guard in either the "shaving" or "out of shaving" position, the arrangement of the spring control being such that in the former position of the guard, variations within limits of the shaving position of the guard is 25 yieldingly permitted by the spring, whereby the amount of projection of the forward end of the guard beyond the cutting edge of the blade can be varied by moving the blade as in the manner before described, the guard 30 automatically yielding in accordance with such movement, and, in the desired adjusted positions of the blade and guard, the spring is effective to prevent vibratory movement of the blade and the guard.

According to the construction of safety 35 razor illustrated by Figs. 1 to 5 of the drawings, the said spring control conveniently comprises a strong wire spring 10 secured at the portion 11 between the handle 4 and the 40 U-frame 3, the handle being connected to the frame 3 by means of the headed thimble-piece 11^a which passes through an aperture in the said frame and is screw threaded for engagement with the handle 4. This spring 45 10 is connected to projections 12 on the guard 9 by means of links 13, in such manner that when the guard is in the shaving position the spring not only tends to retain the guard in such shaving position, but also 50 when the guard is moved down against the handle, tends to retain the guard in such position.

According to the modified construction of 55 safety razor illustrated by Figs. 6 to 10 of the drawings, the spring control conveniently comprises a strong spiral spring 15 arranged around the rod 7 in the tubular handle 4 and the cap or thimble piece 14. The lower end of the spring 15 rests against 60 the part 16 of the cap 14 and the upper end thereof bears against the underside of a stepped sleeve 17 which is mounted in the tubular handle 4. The sleeve 17 is free to slide on the rod 7 and within the tubular 65 handle 4; an appropriate clearance being

left between the sleeve 17 and the inner walls of the tubular handle 4 and the rod 7 respectively. Balls 18 are interposed in the sleeve 17 and are adapted to slide on the rod 7 and the inner wall of the handle 4; the object of the balls 18 being to facilitate the 70 sliding of the sleeve 17 by preventing the rod 7 from contacting with the sleeve 17 when the rod 7 is being subjected to side thrust. The upper part 19 of the sleeve 17 75 passes through and out of a headed thimble piece 20 which extends through an aperture in the frame 3 and is screw threaded for engagement with the handle 4. The upper part 19 of the sleeve 17 is connected to projections 21 on the guard 9 by means of links 22 pivotally secured to the part 19 and the projections 21. When the guard 9 and blade 2 are in the "shaving" position the spring 80 will be compressed between the part 16 of the thimble piece 14 and the lower end of the sleeve 17 thereby not only tending to retain the guard in such "shaving" position, but also when the guard is moved down against the handle, will tend to retain the guard in 85 such position. To prevent any twisting action being imparted to the rod 7, convenient means may be provided, and such means preferably consisting of a pin 23 secured to the rod 7 and adapted to work in a slot 24 90 of the sleeve 17.

In cases where the tail piece 5 is desired to lie exactly in the plane of the blade the expedient may be adopted as illustrated in Fig. 10 of providing a projection 25 on the 100 guard 9 for exerting a push or kick upon the tail piece 5 of the blade holder to push this over the dead center, when the guard 9 is moved from the "stropping" into the "shaving" position, it being necessary to 105 previously release the tension on the tail piece to admit of such a functioning of the guard.

The guard is preferably provided with side lugs 9^a to prevent injury to the shaver 110 by the corners of the blade.

In the case where facilities varying the amount of projection of the guard beyond the cutting edge of the blade are not required only a fixed movement of the rod is 115 wanted but in order to insure precision of adjustment and to prevent vibratory movement of the guard a spring control of the kind referred to is combined with the guard.

As indicated in Figs. 1 or 6 the adjustment of the blade in relation to the guard may be made under the guidance of a scale and pointer respectively furnished on the handle 4 and the cap 14.

With a razor constructed substantially as 125 hereinbefore described there is realized the advantage of compactness for packing with the blade lying against the guard and having the protection thereby afforded by the guard, as the construction admits of the 130

blade and guard being folded down toward the frame to lie nearly parallel therewith. The additional advantage is also afforded of avoiding impact of the blade and the guard 5 one against the other when brought into shaving relationship. A further advantage derived by the preferred illustrated embodiment is that the blade may be raised into the stropping or cleaning position without 10 bringing the hand of the user into contiguity with the cutting edge.

It will further be observed with particular reference to Fig. 5 or 10 that an especially rigid supporting of the blade in the stropping position is realizable in virtue of the 15 end tensioning of the rod 7 by the link 6 and tail piece 5.

Having thus described our invention what we claim and desire to secure by Letters 20 Patent is:—

1. A safety razor of the kind described including in combination, a handle, a guard, a blade holder and a blade carried thereby, said blade being movable independently of 25 the guard into the "shaving" and "stropping" positions, means passing down and movable longitudinally of the handle and connected to the blade holder for rotating it, and means for holding said blade holder 30 actuating means against movement to prevent any substantial displacement of the blade when in either its "shaving" or "stropping" position.

2. A safety razor of the kind described 35 including in combination, a handle, a guard, a blade holder and a blade carried thereby, said blade being movable independently of the guard into the "shaving" and "stropping" positions, means passing down and movable longitudinally of the handle and 40 linked to the blade holder for rotating it, and means for holding said blade holder actuating means against movement to prevent any substantial displacement of the 45 blade in either its "shaving" or "stropping" position.

3. A safety razor of the kind described including in combination, a handle, a guard and a blade carried thereby, said blade being 50 movable independently of the guard into the "shaving" and "stropping" positions, a blade holder having a tail piece lying in the plane of the blade and means for exerting end tension on said tail piece to rigidly hold 55 the blade holder against displacement in either direction when in the "stropping" position.

4. A safety razor of the kind described 60 including in combination, a handle, a guard and a blade carried thereby, said blade being movable independently of the guard into the "shaving" and "stropping" positions, a blade holder having a tail piece lying in the plane of the blade and means passing 65 down and movable longitudinally of the

handle and linked to the tail piece for exerting end tension on said tail piece to rigidly hold the blade holder against displacement in either direction when in the "stropping" position.

5. A safety razor of the kind described including in combination, a handle, a guard, a blade holder and a blade carried thereby, said blade being movable independently of the guard into the "shaving" and "stropping" positions, means passing down and movable longitudinally of the handle and connected to the blade holder for rotating it, and means for effecting an adjustment of the parts in the shaving position thereof by manipulation of the said blade holder actuating means whereby the amount of projection of the guard beyond the edge of the blade may be varied.

6. A safety razor of the kind described 85 including in combination, a handle, a guard, a blade holder and a blade carried thereby, said blade being movable independently of the guard into the "shaving" and "stropping" positions, means passing down and 90 movable longitudinally of the handle and linked to the blade holder for rotating it, and means for effecting an adjustment of the parts in the "shaving" position thereof by manipulation of the said blade holder 95 actuating means whereby the amount of projection of the guard beyond the edge of the blade may be varied.

7. A safety razor of the kind described including in combination, a handle, a guard, 100 a blade holder and a blade carried thereby, said blade being movable independently of the guard into the "shaving" and "stropping" positions, means passing down and 105 movable longitudinally of the handle and connected to the blade holder for rotating it, elastic means for preventing vibratory movement of the guard in relation to the blade when the parts are in "shaving" 110 relationship, and means for holding said blade holder actuating means against movement to prevent any substantial displacement of the blade when in either its "shaving" or "stropping" position.

8. A safety razor of the kind described 115 including in combination, a handle, a guard, a blade holder and a blade carried thereby, said blade being movable independently of the guard into the "shaving" and "stropping" positions, means passing down and 120 movable longitudinally of the handle and linked to the blade holder for rotating it, elastic means for preventing vibratory movement of the guard in relation to the blade when the parts are in "shaving" 125 relationship, and means for holding said blade holder actuating means against movement to prevent any substantial displacement of the blade in either its "shaving" or "stropping" position.

9. A safety razor of the kind described including in combination, a handle, a guard, a blade holder and a blade carried thereby, said blade being movable independently of the guard into "shaving" and "stropping" positions, a reciprocatory member passing down the handle and connected to the blade holder for rotating the latter, lockable finger actuated means for reciprocating said member for holding said reciprocatory member against movement to prevent any substantial displacement of the blade when in either its "shaving" or "stropping" position, a sleeve connected to the guard and slidably located within said handle and spring means acting on the said sleeve.

10. A safety razor of the kind described including in combination, a handle, a guard, a blade holder and a blade carried thereby,

said blade being movable independently of the guard into "shaving" and "stropping" positions, a reciprocatory member passing down the handle and connected to the blade holder for rotating the latter, lockable finger actuated means for reciprocating said member for holding said reciprocatory member against movement to prevent any substantial displacement of the blade when in either its "shaving" or "stropping" position, a sleeve linked to the guard and slidably located within said handle and spring means acting on the said sleeve. 25 30
